[57] CLAIM

The ornamental design for a plant saucer for multiple plant groupings, as shown and described.

DESCRIPTION

FIG. 1 is a top plan view of the plant saucer for multiple plant groupings, showing the new design;

FIG. 2 is a side elevational view thereof; an elevational view of the opposite side is identical;

FIG. 3 is a bottom plan view thereof;

FIG. 4 is an end elevational view thereof; an elevational view of the opposite end is identical;

FIG. 5 is a top plan view of the plant saucer for multiple plant groupings showing an alternate embodiment of the new design as transparent;

FIG. 6 is a side elevational view of the alternate embodiment of FIG. 5 of the new design; an elevational view of the opposite side is identical;

FIG. 7 is a bottom plan view of the alternate embodiment of FIG. 5 of the new design; and,

FIG. 8 is an end elevational view of the alternate embodiment of FIG. 5 of the new design; an elevational view of the opposite side is identical.
